Primary Examiner — Mary Ann Calabrese*Assistant Examiner* — Katelin G Kloberg(74) *Attorney, Agent, or Firm* — Cook Alex Ltd.; R. Blake Johnston(57) **CLAIM**

The ornamental design for a table, as shown and described.

DESCRIPTION

FIG. 1 is a perspective view of the table;
 FIG. 2 is a front elevational view of the table, the rear, left side and right side elevational views of which being identical;
 FIG. 3 is a top plan view of the table; and,
 FIG. 4 is a bottom plan view of the table.
 The broken lines shown in the drawings depict portions of the table and form no part of the claimed design.

1 Claim, 4 Drawing Sheets(56)
